(57) **CLAIM**

We claim the ornamental design for a lantern, as shown and described.

DESCRIPTION

FIG. 1 is a perspective view of a lantern;

FIG. 2 is a top plan view of the lantern;

FIG. 3 is a front elevation view of the lantern;

FIG. 4 is a right side elevation view of the lantern;

FIG. 5 is a rear elevation view of the lantern;

FIG. 6 is a left side elevation view of the lantern; and,

FIG. 7 is a bottom plan view of the lantern.

The broken lines shown in the drawings depict portions of the lantern that form no part of the claimed design.
